APPARATUS FOR PICKLING AND CLEANING
STRIP METAL

Frank J. Wood, Riverside, Ill., assignor to Goodman Manufacturing Company, Chicago, Ill., a corporation of Illinois

Application February 18, 1938, Serial No. 191,167

4 Claims. (Cl. 266—7)

Heretofore, pickling apparatus for strip metal have been so arranged as to take care of one type of pickling fluid only. Thus, when it is desired to pickle different kinds of metals which require different pickling solutions, it has been necessary to stop the apparatus and thoroughly clean it out after the completion of the pickling operation for each kind of metal. This is particularly true with different kinds of non-ferrous materials; as for instance, copper and brass. They each require a different type of solution and if the storage tank is not thoroughly cleaned after the pickling of the copper, the brass will become discolored by the acid from the copper pickling solution, if it is pickled after the copper.

Among the objects of my invention is to provide an apparatus which will permit the pickling of a number of different kinds of metals, rendering it unnecessary to drain and clean the pickling fluid from the system when changing from the pickling and cleaning of one kind of metal to another.

A more specific object of my invention is to provide a pickling bath which consists of a pickling trough extending along a receptacle or storage reservoir adapted to contain a number of kinds of pickling fluids, and including means associated with the pickling trough for selectively conducting the pickling fluid to the desired part of the storage reservoir during the pickling operation so that the pickling of different materials may be effected without the delay of emptying and cleaning the pickling fluid from the storage reservoir before starting the pickling operation of a different metal.

Other objects of my invention will appear from time to time as the accompanying specification proceeds.

My invention may best be understood by referring to the accompanying drawings wherein:

Figure 1 is a diagrammatic plan view of a pickling and cleaning apparatus for strip metal constructed in accordance with my invention;

Figure 2 is an enlarged fragmentary plan view of the pickling bath with certain parts thereof broken away;

Figure 3 is an enlarged sectional view taken substantially along line 3—3 of Figure 1;

Figure 4 is an enlarged sectional view taken substantially along line 4—4 of Figure 1;

Figure 5 is a transverse sectional view taken substantially along line 5—5 of Figure 1; and

Figure 6 is an enlarged detail view showing certain details of construction of the apparatus.

In the drawings the embodiment of my inven-

tion illustrated includes a coil supporting box 10 at the entering end of the cleaning apparatus which forms a support for a coil of metal 11, permitting it to be unwound and pass through the cleaning apparatus. From said coil supporting box the metal passes through a leveler 12 for leveling and straightening the metal before the cleaning operation, which includes a plurality of power driven leveling rolls 13, 13. It then passes through a pickling bath 14 where it is given a uniform bath of pickling acid on all sides. Surplus acid is removed from the metal by means of squeegee rolls 15, 15, rotary brushes 16, 16, and squeegee rolls 17, 17. From thence the metal passes through a drier 18 and squeegee rolls 19, 19 to a coiler generally indicated by reference character 20 which recoils it. Said coil supporting box, leveler, squeegee rolls, brushes, drier and coiler are only shown in an illustrative manner, and the details thereof will not be herein shown or described since they form no portion of the present invention.

The pickling bath 14 includes a longitudinally extending tank 21 having a partition 22 extending along the central portion thereof to form two storage chambers for the pickling fluid, arranged side by side. Said tank and partition are lined with an acid resisting composition such as rubber or any other suitable composition. A suitable base is provided for said tank which includes a pair of spaced apart transversely extending supporting members or channels 23, 23, upon which said tank is mounted. Said channels are mounted on I beams 24, 24 extending longitudinally of said tank.

A pickling trough 25 is disposed above and extends along said tank and forms a means through which the strip metal passes during the pickling operation. Said pickling trough, as herein shown, is supported on a plurality of transversely extending channels 26, 26 supported at their ends on the upper ends of pipes 27, 27 which form supporting columns for said channels. Said pipes are mounted on the outer ends of the cross members 23, 23 in a suitable manner, such as welding (see Figures 5 and 6). Retaining members 29, 29 are secured at their lower ends to the upper sides of the support members 26, 26 adjacent the outer ends thereof and extend angularly upwardly along the sides of the pickling trough 25 for retaining said trough on said channels. A cover 30 is provided to completely enclose the top of said trough.

The tank 21 is provided with a drain 33 in its bottom on one side of the partition 22, and a similar drain 34 in the opposite side of said par-

tion. Suitable valves, herein shown as being stoppers 35, 35, are provided to close either of said drains. Each of said drains leads to a common pipe 36 which leads to a T 36a (see Figures 2 and 5).

One opening of the T 36a leads to a fluid pressure pump 37. Said pump is adapted to supply pickling fluid under pressure to the pickling trough 25 and may be of any type well known to those skilled in the art and is no portion of my present invention so will not herein be described in detail.

The other opening of the T 36a serves as an outlet for draining either side of the tank 21 or as an intake for filling either side of said tank with pickling fluid. Draining of either tank for cleaning, or the replacing of one type of pickling fluid in one side of the tank 21 with another, may thus be effected without disturbing the fluid in the other side of said tank. Both drains 33 and 34 are adapted to be closed when refilling the empty side of the tank with the desired type of pickling fluid.

It should be understood that a valve 36b is provided in the line leading from the draining branch of the T 36a, which is closed when circulating the pickling fluid through the system.

Pickling fluid under pressure is conducted from the pump 37 to the trough 25 through a pipe 39 which is herein shown as having connection with a pipe 40 at substantially its transverse center. The latter pipe extends longitudinally along the center of the pickling trough and is provided with a plurality of outlets 41, 41 disposed along its length and leading through the bottom of the pickling trough 25. Said openings are so formed as to permit pickling fluid under pressure entering said pickling trough to engage the underside of the metal and buoy it up as it passes therethrough, and at the same time to create sufficient turbulence that the metal will be entirely submerged in the pickling fluid.

Referring now in particular to the means for selectively conducting fluid from the trough 25 to the desired portion of the tank 21, and certain other novel features of my invention, a tilting fluid deflecting trough 44 is provided beneath the entering end of the pickling trough 25. Said tilting trough is supported beneath a covering 45 for the sides and entering end of said pickling trough. Said covering includes an end wall 46 spaced from and extending across the entering end of the trough 25 and having an opening 47 therein, through which the metal which is being pickled passes. The end wall 46 of said covering and sides 49 thereof extend beneath the bottom of the trough 25 and inwardly within the inside of the tilting trough 44 to form a restricted conduit leading to said tilting trough.

The tilting trough 44 is rockingly supported on the upper end of the partition 22 on a pair of rocking support members 50, 50, resting on said partition and herein shown as being of a substantially inverted V-shaped formation. Said trough is selectively tilted or held in the desired position of adjustment with respect to the tank 21 by means of an arm 51 secured to the inner side of said trough and extending angularly upwardly and inwardly therefrom. The upper end of said arm is pivotally connected to a link 53 which is adapted to be hand operated for tilting said trough manually (see Figure 2 and 4). A bracket 55 is secured to and depends from the outer end of the channel 26 and has a hook shaped end adapted to be engaged by certain

spaced notches (not shown) formed in the underside of said link.

In a like manner a tilting fluid deflecting trough 57 is provided at the discharge end of the pickling trough 25. Said tilting trough is disposed beneath a centering and guiding member 58 which is similar to that shown in a prior application Serial No. 165,016, filed September 22, 1937, now Patent No. 2,141,732, so will not herein be described, excepting to point out that it includes two adjustable pivoted guide members 59, 59 having curved outer sides extending over the upper side of the metal and being adapted to engage the sides thereof for guiding the metal through the pickling bath.

The sides and end of the discharge end of the pickling trough 25 are covered by a covering 60 which is similar to that covering the entering end of said trough. Said covering extends from a point disposed ahead of the squeegee rolls 15, 15 and rearwardly along the centering guide 58 to a point beyond the rear end thereof (see Figure 3). An opening 62 is provided in the forward end of said covering to permit the metal to pass from the squeegee rolls 15, 15 to the brushes 16, 16. The lower portion of said covering extends inwardly from the sides and forward end thereof and is provided with a depending restricted portion 63 which extends within the sides of the tilting trough 57 and forms a conduit for guiding the pickling fluid into said trough.

The tilting trough 57 is supported on the partition 22 on a pair of spaced apart rocking support members 64, 64 similar to the members 50, 50. Said trough is tilted by means of an arm 65 which extends inwardly and upwardly from the inner side thereof. The free end of said arm is pivotally connected to a control link 66 for manually actuating said arm and tilting said trough. Said control link is provided with a plurality of notches 67, 67 open to the underside thereof which are adapted to have selective engagement with the hooked lower end of a rod 68 depending from the support member 26 for holding said tilting trough in the desired position with respect to the tank 21.

It will be seen from the foregoing that when one metal is passing through the pickling trough 25, the tilting collecting troughs 44 and 57 are tilted in the same direction to discharge the pickling fluid into the desired section of the tank 21, and when another metal is passing through the system, which requires another type of pickling solution, the tilting troughs 44 and 57 are tilted in an opposite direction to collect and discharge the pickling fluid in the opposite side of said tank.

When it is desired to pickle a different kind of metal than formerly, it is simply necessary to close the drain of the section of the tank which has been formerly used and pump the pickling fluid from the system and drain it from the trough 25 into said closed section of said tank. The trough 25 should then be cleaned in any suitable manner. The tilting troughs 44 and 57 are then tilted to discharge fluid in the opposite section of the tank 21 from the section which was used before, and the stopper in said section of said tank is removed to permit the pickling of the other kind of metal with the proper pickling solution.

It will thus be seen that a new and improved device for pickling metal has been provided which is so arranged that one storage tank may be used for different types of pickling solutions.

and that the pickling solution passing through the system may be selectively discharged into one side or the other of said tank as desired, to enable the pickling of different kinds of metal 5 with a minimum delay between pickling operations.

While I have herein shown and described one form in which my invention may be embodied, it will be understood that the construction 10 thereof and the arrangement of the various parts may be altered without departing from the spirit and scope thereof. Furthermore, I do not wish to be construed as limiting myself to the specific embodiment illustrated, excepting 15 as it may be limited in the appended claims.

I claim as my invention:

1. In a continuous pickling and cleaning device for strip metal, an open end pickling trough through which the strip metal is adapted to pass, 20 a tank disposed beneath said trough and adapted to receive fluid discharged from the ends of said trough, a partition extending along said tank to form separate storage reservoirs in said tank for more than one kind of pickling fluid, means for 25 conducting fluid from a selective one of said storage reservoirs to said pickling trough, and a fluid collecting member disposed beneath the discharge end of said pickling trough, said collecting member being rockingly mounted on said 30 partition, and having manually controllable means to tilt said collecting member and permit the selective discharge of the pickling fluid into the desired fluid storage reservoir in said tank, to permit the use of different pickling solutions 35 without draining the solutions from said tank.

2. In a continuous pickling and cleaning device for strip metal, an open end pickling trough through which the strip metal is adapted to pass, 40 a tank disposed beneath said trough and adapted to receive fluid discharged from the entering and receiving ends of said trough, a partition extending along said tank to form separate storage reservoirs in said tank for more than one kind of pickling fluid, means for 45 conducting fluid from a selective one of said storage reservoirs to said pickling trough, and a plurality of collecting members, one of said members being disposed beneath the discharge end of said pickling trough and the other 50 of said members being disposed beneath the entering end of said pickling trough, said members being rockingly mounted on said partition adjacent opposite ends thereof and having man-

ually controlled means to control the discharge of the pickling fluid from said collecting means into the desired fluid storage reservoir in said tank and permit the use of different pickling solutions without draining the solutions from said 5 tank.

3. In a continuous pickling and cleaning device for strip metal, a fluid storage tank having two fluid storage reservoirs, an open end pickling trough through which the strip metal is adapted 10 to pass, means for conducting fluid from a selective one of said storage reservoirs to said pickling trough, said trough being mounted on said tank and being arranged to permit pickling fluid to flow into said tank from the ends of said trough, 15 a partition extending along said tank to form separate storage reservoirs for more than one kind of pickling fluid, means for conducting fluid discharged from said trough to either of said storage reservoirs in said tank including a tilting 20 trough disposed beneath the discharge end of said pickling trough and having a rocking support member depending therefrom and rockingly resting on said partition, to permit tilting of said trough on said partition about an axis extending 25 longitudinally of said tank, and manually controllable means to tilt said trough and hold it in a tilted position, to permit the selective discharge of pickling fluid in the desired fluid storage reservoir in said tank. 30

4. In a continuous pickling and cleaning device for strip metal, a fluid storage tank having two fluid storage reservoirs, an open end pickling trough through which the strip metal is adapted 35 to pass, means for conducting fluid from a selective one of said storage reservoirs to said pickling trough, said trough being mounted on said tank and arranged to permit pickling fluid to flow into said tank from opposite ends of said trough, a partition extending along said tank to 40 form separate storage reservoirs for more than one kind of pickling fluid, means for collecting fluid discharged from the ends of said trough and conducting it to either of said storage reservoirs in said tank including a pair of tilting troughs 45 rockingly mounted on said partition adjacent opposite ends thereof and beneath opposite ends of said pickling trough, and manually controllable means to tilt said troughs and hold them in a tilted position, to permit the selective discharge of pickling fluid in the desired storage reservoir 50 in said tank.

FRANK J. WOOD.
